UNITED STATES PATENT OFFICE.

OSCAR ONSRUD, OF CHICAGO, ILLINOIS.

GRINDING-MACHINE.

1,341,818.

Specification of Letters Patent.

Patented June 1, 1920.

Application filed June 23, 1919. Serial No. 308,074.

To all whom it may concern:

Be it known that I, OSCAR ONSRUD, a citizen of the United States of America, and a resident of Chicago, county of Cook, and 5 State of Illinois, have invented certain new and useful Improvements in Grinding-Machines, of which the following is a specification.

This invention relates to that class of automatic machinery wherein the work is placed in a holder and moved relatively of a tool so that said work is cut, shaped, or otherwise acted upon by said tool.

The main objects of this invention are to 15 provide an improved machine of this kind having an improved arrangement of the tool and the driving means therefor; to provide improved means for controlling the supply of power to the tool-operating motor so as 20 to minimize as much as possible the consumption of power; to provide an improved construction and arrangement of the work support; to provide improved means for clamping the work in place during the action 25 of the tool thereon; to provide improved means for effecting the discharge of the completed article and feeding the work; to provide improved mechanism for advancing the work on the work support to 30 compensate for the wearing away of the tool and thereby insure the complete operation of the tool upon the work at all times; and to provide an improved construction and arrangement of means for reciprocating the 35 work and controlling the clamping means.

An illustrative embodiment of this invention is shown in the accompanying drawings, in which—

Figure 1 is a longitudinal vertical sectional elevation of an improved machine constructed in accordance with this invention.

Fig. 2 is a transverse vertical sectional elevation of the same taken on the line 2—2 45 of Fig. 1.

Fig. 3 is a top plan of the improved machine.

Fig. 4 is a front elevation of the work clamping means and adjacent parts.

50 Fig. 5 is an enlarged detail of the "take-up" mechanism.

Fig. 6 is a fragmentary sectional detail showing the arrangement of air and liquid passages in the work support.

55 Fig. 7 is a detail view of the valve mecha-

nism which controls the air to the turbine and to the air blast respectively.

Fig. 8 is an enlarged fragmentary front elevation of one pair of jaws showing the arrangement of the mechanical discharging 60 device for the finished article.

Fig. 9 is a plan of the same.

In the specific embodiment herein shown, the machine comprises a frame A whereupon is mounted a tool-operating mechanism B and a work support C, which are operated, as will more fully hereinafter appear, for the purpose of causing a metal rod carried by the work support to be cut into thin disks. Although the machine illustrated is generally known as a grinder, it will be understood that the improvements are capable of being applied to other machines.

The frame A is shown in the drawings to 75 be a hollow pedestal 1 integrally formed on a base 2, to which a bracket 3 is attached for supporting the tool-operating mechanism B and the upper end of which is shaped to provide a bed plate 4 upon which the work support C is reciprocatingly mounted.

The tool operating mechanism B comprises a tool 10 carried by a vertically disposed shaft 5 journaled in a bearing 6 formed on the bracket 3 and rotated by a 85 motor D. The tool is herein shown as an emery disk and is secured to a tool holder 7, consisting of a pair of plates 8 and 9, attached to the upper end of the shaft 5.

The motor D, which rotates the tool, is 90 preferably an air turbine of the type shown in the Ross and Onsrud Patent No. 1,244,247, issued October 23, 1917. Such a motor comprises a rotor 11 journaled in a casing 12 and having a plurality of air jets 13 angularly arranged around said casing for the purpose of directing jets of air against the vanes of the rotor. The delivery of air to the motor is automatically controlled, as will more fully hereinafter be explained.

In order to maintain a more or less constant speed for the tool, the shaft 5, below the turbine, is connected to a centrifugal governor 14 which functions in the usual manner.

The work support C comprises a pair of relatively adjustable parts 15 and 16, one of which carries a work holder 19 and clamping means for holding the work in place, and also a "take-up" mechanism adapted 105 110

to advance the work on the support so as to compensate for the wearing away of the tool.

The part 16 is of I-shaped cross-section, 5 and the lower portion fits with and slides upon the bed plate 4 for the purpose of enabling the work to be shifted back and forth with respect to the tool. The part 15 is of substantially T-shaped cross-section, 10 with the stem part slidingly fitting on the upper portion of the part 16.

The reciprocation of the work support is effected by means of a cam 17 secured to a shaft 18 rotatably mounted within the pedestal of the frame A and a spring 17.1 and lever 17.2 also mounted in said pedestal. The cam 17 bears upon a roller 18.1 journaled on a pin 18.2 rigidly secured to the part 16 and is adapted to urge the work support outwardly against the action of the spring 17.1. The lever 17.2 bears, at its middle part, against the pin 18.2 above the roller 18.1 and has one end resting upon the pedestal 1 and the other end connected to the spring 17.1. 25 Through the coaction of the spring 17.1 and lever 17.2, the work support is normally urged rearwardly on the bed plate 4 as permitted by the cam 17.

The work holder 19 is mounted on the forward end of the support C in a vertically disposed position and is adapted to have the work fed therewith by means of gravity. A stop 20 is arranged below the holder in alinement therewith, against which the 35 work abuts for limiting its feeding movement. The stop consists of a bolt 21 threadingly mounted in the lug 22 and adapted to be secured in place by a lock nut 23.

The clamping means for holding the work 40 in place comprises jaws 24, 25, 26, and 27 arranged in pairs on the forward end of the work support adjacent to the stop 20, with their opposed faces alined with the work holder 19. The pairs of jaws are spaced 45 apart vertically a distance slightly more than the thickness of the tool, which in this case is the emery disk 10, so that said pairs of jaws grip the work on opposite sides of the point upon which the tool operates. The 50 jaws 24 and 26 are shiftably mounted on the work support so as to be adjusted by the adjusting screws 28 and 29 respectively, and be fixed in their adjusted positions by stud bolts 30 and 31 respectively. The jaws 25 and 27 are secured to blocks 32 and 33 respectively, pivotally mounted at 34, whereby 55 said jaws are adapted to be swung toward and away from the fixed jaws 24 and 26 for the purpose of clamping or releasing both 60 the finished article and the work.

The shifting of the jaws 25 and 27 is controlled by a pair of arms 35 and 36, levers 37 and 38, levers 37.1 and 38.1, and cams 39 and 40 respectively. The arms 35 and 36 65 are secured at their forward ends to the

blocks 32 and 33 respectively and have their rearward ends slidingly bearing upon spring-pressed pins 41 and 42 mounted on a bracket 43 secured to the side of the frame A. The spring-pressed pins 41 and 42 normally urge the arms 35 and 36 inwardly as may be permitted by the cams 39 and 40, which serves to open the jaws 25 and 27. The levers 37 and 38 are concentrically mounted upon a shaft 44 journaled on 75 the bracket 43, and by means of concentrically mounted sleeves are connected to the levers 37.1 and 38.1 respectively. The levers 37 and 38 have rollers 37.2 and 38.2 carried thereby, which bear against the 80 inner faces of the arms 35 and 36 respectively. The levers 37.1 and 38.1 extend into the pedestal 1 and carry rollers 37.4 and 38.4 which bear against the cams 39 and 40 respectively. The cams 39 and 40 are carried 85 by the shaft 18 and are shaped so that during a part of their rotation they will cause the levers 37.1 and 38.1 and the levers 37 and 38 to normally urge the arms 35 and 36 outwardly 90 against the action of the spring-pressed pins 41 and 42, and thereby urge the jaws into position to clamp the work, and during another part of their rotation will permit the spring-pressed pins 41 and 42 to retract the arms 35 and 36 so as to shift the jaws 25 and 95 27 into their retracted positions for releasing the work. The relative shape and arrangement of the cams 39 and 40 are such that the jaw 25 is retracted slightly in advance of the retraction of the jaw 27, so as to enable 100 the finished article to be released and discharged before the work is released by the jaws 26 and 27 for the purpose of being advanced preliminary to a further operation.

For the purpose of facilitating the discharge of the finished article from the work support after it has been released by the clamping jaws 24 and 25, an air blast and a liquid spray (water or oil) are arranged on the work support C in such a way that either 105 may be used as occasion may demand, which may be replaced or supplemented by a mechanical discharge.

The air blast comprises a channel 45 leading inwardly from the side of the part 15 of the work support C and then forwardly as at 45.1, opening rearwardly of the jaws 24, 25, 26, and 27 in alinement with the space between the opposed faces of said jaws. The supply of air to the air blast is 110 controlled by an automatically operated valve mechanism more fully hereinafter described.

The liquid spray comprises a tank 48 mounted on a stem 49 above the work support C and has a tube 50 leading therefrom and connecting with a T-fitting 47 secured to the part 15 of the work support C so as to communicate with a channel 51 (see Fig. 6) formed therein and having a branch 51.1 125 130

opening directly behind the jaws 24, 25, 26, and 27. A second branch of the liquid spray comprises a nozzle 46 (see Fig. 3) supported on the T-fitting 47 and having the end 5 thereof located forwardly of the jaws 24, 25, 26, and 27 and to one side of the work so that a jet of liquid issuing therefrom is at an angle of about 45° to the jet of liquid issuing from the channel 51.1. Liquid is 10 fed by gravity to the T-fitting 47, from whence the liquid passes to the channel 51 and the nozzle 46 and is discharged onto the work from the branch 51.1 and the end of the nozzle 46 simultaneously. During 15 the operation of the tool upon the work, the liquid serves to cool the same, but when the part has been severed from the work and the tool retracted, the jets of liquid have sufficient force to wash the finished article 20 off from the stop 20, upon its being released by the jaws 24 and 25. A valve 52 is arranged in the tube 50 for the purpose of controlling the flow of liquid from the tank 48. Some kinds of work require the use of 25 liquid for cooling the same, and at such times the air blast is not used. Where, however, the work does not require the use of liquid, air is used.

The mechanical discharge comprises a 30 piece of very thin metal (about .002 of an inch) bent in the form of an angle plate 20.1 and secured to the jaw 25 by the bolt which secures said jaw to the block 32. A hook 20.2 extends outwardly from the plate 35 20.1 to the rear of the work and across onto the jaw 24. The curvature of this hook is substantially the same as the diameter of the work, whereby when the jaw 25 swings to release the finished article, said hook sweeps 40 the same off from the stop 20 in case the air blast or liquid jet has not done so.

A tray 53 is mounted on the pedestal 1 and bracket 3 below the work support, which tray is adapted to catch the liquid as 45 it runs off from the clamping means and adjacent parts. A drain 54 is arranged at one corner of the tray, from which a tube or pipe 55 leads to a small centrifugal pump (not shown) by means of which the liquid 50 is returned to the tank 48. This tray also catches the finished articles as they are discharged from the work support.

The "take-up" mechanism for advancing the work toward the tool to compensate for 55 wear of the tool comprises primarily an adjusting screw member 56, an oscillating member 57, and a cam 58. The threaded screw member 56 is swiveled to the part 15 and has threaded connection with a nut 59 60 rigidly secured to the part 16 so that the rotation of said threaded member in one direction or the other causes a corresponding relative shifting of the parts 15 and 16. The oscillating member 57 is journaled on 65 the screw member 56 beyond the end of the

part 15 and is provided with pawls 60, 61, and 62, which are adapted to coact with a ratchet 63 secured to said screw member. The pawls 60, 61, and 62 are of varying lengths so that one of the pawls is always 70 positively engaged with a tooth on the ratchet which insures some advance of the threaded member for each oscillation of the member 57, which is likely to be less than the angularity of the teeth on said ratchet. 75 The pawls 60, 61, and 62 are normally urged into contact with the ratchet by counterweights 64, 65 and 66 respectively, integrally secured thereto.

In order to enable the pawls to be retracted so as to discontinue the rotation of the threaded bolt after the members 15 and 16 have been relatively shifted to a predetermined extent or to allow the threaded member to be rotated for the purpose of resetting the parts 15 and 16, a rod 67 is shiftably mounted on the oscillating member 57 and has a pin 68 at the lower end, which, when the rod is urged upwardly by the spring 69, is adapted to elevate the counterweight 64 of the pawl 60. Shoulders 70 and 71 on the counterweights 64 and 65 are thereupon adapted to coact with the counterweights 65 and 66 respectively for elevating the same and retracting the corresponding 95 pawls 61 and 62. The rod 67 is held in its depressed position by means of a pawl or finger 72 pivoted at 73 on the oscillating member 57 so as to engage a notch 74 formed in the side of the rod 67. 10

The finger or pawl 72 is normally urged by a spring 75 (see Fig. 1) embracing a shaft 76 which carries said finger, into position to engage the notch 74 for holding the rod 67 in its depressed position. The retraction of the finger 72 for the purpose of releasing the rod 67 may be effected either manually or automatically. To this end, an L-shaped lever 77 is secured to the shaft 76, the arm 77.1 of which extends upwardly 110 and by which one may swing the finger 72 out of engagement with the notch 74. A set screw 78 is secured to the other arm of the lever 77 so that the lower end of said set screw is opposed to and by adjustment may 115 bear upon the upper face of the part 15 of said work support C. A lock nut 79 secures the set screw in proper position in the lever 77. After the oscillating member 57 has been advanced to a certain angular extent by the action of the cam 58, as will 120 more fully hereinafter appear, the contact of the end of the set screw 78 with the upper face of the part 15 causes the finger 72 to be retracted from the notch 74 so as to release the rod 67. 125

The oscillation of the member 57 is effected by means of a roller 80 journaled on a pin 81 secured to the oscillating member 57, which roller operates in the elongated 130

cam 58 secured to the rear end of the pedestal 1 below the reciprocating work support C. The cam 58 is of arcuate shape with regard to its longitudinal dimension, the center of curvature being the axis of the screw member 56. Said cam is supported in such a way as to be adjusted in a horizontal plane for the purpose of varying the angularity thereof with respect to the direction of movement of the reciprocating work support C and thereby vary the degree of oscillation of the member 57.

A hand wheel 82 is secured to the rear end of the screw member 56 by means of which said member may be turned independently of the automatic operation thereof effected by the oscillating member 57.

The supply of air to the turbine, which operates the tool, and to the air blast, is controlled by valve mechanisms 83 and 84 (see Fig. 7) secured to the sides of the pedestal 1. At one side these valves are connected to a pipe 85 leading to a source of air supply, and at the other sides are connected by pipes 86 (see Fig. 3) and 87 leading to the turbine D and the channel 45 respectively. These valve mechanisms are practically the same in construction, each comprising a casing 88 (see Fig. 2) having a channel leading therethrough for the purpose of providing communication between the pipe 85 and the pipes 86 and 87 respectively, which communication is controlled by a valve 89 normally urged by a spring 90 into its closed position.

Levers 91 and 92 are pivoted on the pedestal 1 on a common axis 93 so that one end of each of said levers is directly above and adjacent to the upper ends of the valve stems of the respective valve mechanisms 83 and 84. The other ends of the levers 91 and 92 extend into the pedestal 1 and are adapted, through the medium of pins 91.1, and 92.1, to engage a cam 94 secured to the shaft 18. The cam 94 is grooved in its upper face for a part of its circumference so that during a part of its angular movement it is adapted to allow the valve mechanisms 83 and 84 to be closed, and during another part of its angular movement to open said valve mechanisms. The arrangement of the cam and levers is such that the opening of the valve mechanism 83 will occur during the time that the work is being moved toward the tool and operated upon. The opening of the valve mechanism 84 will occur simultaneously with the retraction of the work-clamping means, so that the air jet issuing from the channel 45.1 will discharge the finished article from the stop 20 upon its release by the jaws 24 and 25.

The shaft 18 is journaled in suitable bearings in the pedestal 1 and at its lower end carries a gear 95 which meshes with a worm 96 carried on the shaft 97, which in turn

carries a cone-pulley 98 and which is adapted to be connected by a belt (not shown) with a suitable source of power. Suitable clutch mechanism 99 is arranged between the cone-pulley 98 and the shaft 70 upon which it is mounted, so that said pulley may be connected in driving relation with the machine, as may be desired.

The operation of the device herein shown is substantially as follows:

Assume that the parts are all assembled and properly connected so that the machine is in operation. The emery disk 10 is rotated at a very high rate of speed by the turbine. As the shaft 18 rotates, the cam 17, 80 acting on the roller 18.1, causes the work support C to move forwardly toward the tool. As the work support starts its forward movement, the cam 94, acting on the lever 91, opens the valve mechanism 83, and 85 air is admitted to the turbine so as to bring it up to normal speed before the tool engages the work, and keep the air pressure supplied to said turbine so long as the tool engages the work.

The work moves forward and is engaged by the emery disk so that a small section of the lower end of the work is severed.

As soon as the emery wheel has cut through the work, the work support, under 95 the action of the spring 17.1 and lever 17.2, commences its return movement. Almost instantaneously with the commencement of said return movement, the cams 39 and 40, acting on the levers 37.1, 38.1, 37, and 38, 100 permit the spring-pressed pins 41 and 42 to shift first the arm 35 and then the arm 36. The shifting of the arm 35 retracts the clamping jaw 25 so that the finished article is released.

At the instant the jaw 25 is retracted, the cam 94, acting on the lever 92, actuates the valve mechanism 84 so that air is admitted to the air blast, and a jet of air is discharged from the channel 45.1 so as to blow 110 the finished article off from the stop 20. (If liquid is being used, the air blast is not operated, and the finished article is washed off from the stop by jets of liquid which issue continuously from the channel 51.1 115 and the nozzle 46.)

As the work support C continues its rearward movement, and after a sufficient time has elapsed to insure the discharge of the finished article from the clamping jaws 24, 120 and 25 and the stop 20, the arm 36 is shifted so as to retract the jaw 27, whereupon the work is released and is allowed to move by gravity downward through the holder to abut against the stop 20. As soon as the 125 feeding of the work has been completed, the cams 39 and 40, acting on the levers 37.1, 38.1, 37, and 38, shift the arms 35 and 36 against the action of the spring-pressed pins and move the jaws 25 and 27 into position 130

to clamp the work at both sides of the point at which it is operated upon by the emery disk, and the work support is again ready to be moved forwardly for the purpose of severing another section of the work.

Upon the emery wheel completely severing the part from the work, the cam 94 allows the lever 91 to be retracted under the action of the spring 90, so that the valve mechanism 83 is closed and air is cut off from the turbine until the work support again starts its forward movement. The turbine, operating at the high speed which it does, and being required to do no work while the air is cut off, does not materially reduce its speed during the time that the air supply is cut off.

During the forward movement of the work support C, the roller 80, operating in cam 58, causes the member 57 to oscillate slightly, whereupon one or the other of the pawls 60, 61, and 62, acting on the ratchet 63, causes the screw member 57 to shift the part 15 forwardly on the part 16 and bring the work a little nearer to the tool. During each reciprocation of the work support C, there is a corresponding oscillation of the member 57 and a consequent relative shifting of the members 15 and 16, the result of which is to move the work closer to the tool a sufficient distance to compensate for the wearing away thereof.

It is of course necessary to check the relative shifting of the parts 15 and 16 before they have been moved a sufficient extent to endanger contact of the tool with the part 15. Accordingly, the set screw 78 may be adjusted so that the oscillating member 57, after having been moved to a certain angular extent as the result of its intermittent oscillations, will cause the end of said set screw to bear upon the upper face of the part 15 in such a way as to retract the finger 72 and release the rod 67. Upon the rod 67 being released, it is urged upwardly by the spring 69 so that the pin 62 at the lower end thereof engages the counterweight 64 and shifts it upwardly so as to disengage the pawl 60 from the ratchet 56. The shifting of the counterweight 64 results in a similar shifting of each of the other counterweights 65 and 66 and a consequent retraction of the pawls 61 and 62. The result is that further reciprocations of the work support, although causing an oscillation of the member 57, will not result in a rotation of the screw member 56.

When it becomes necessary to insert a new tool, the parts 15 and 16 are relatively shifted back to their normal position, which is effected by turning the hand-wheel 82, after having released the pawls 60, 61, and 62 from engagement with the ratchet 56. If retraction of these pawls has not been effected automatically, in the manner here-

inbefore explained, it may be done manually by simply pulling the lever arm 77.1 so as to retract the finger 72 from engagement with the shoulder 74 on the rod 67.

After the new tool has been inserted and the parts 15 and 16 restored to their normal relative positions, the "take-up" mechanism may be again placed in operative relation by simply depressing the rod 67 until the notch 74 thereon has been engaged by the finger 72.

Although but one specific embodiment of this invention has been herein shown and described, it will be understood that numerous details of the construction shown may be altered or omitted without departing from the spirit of this invention as defined by the following claims.

I claim:

1. In a machine of the class described, the combination of a frame, a tool support and a work support mounted thereon, mechanism for shifting said supports relative to each other so as to bring the work into position to be acted upon by the tool, a motor for rotating said tool support, a power-controlling device arranged intermediate said motor and the source of power, and means operated by said support-shifting mechanism for actuating said controlling device so as to permit the supply of power to said motor only during a certain portion of the relative movement of said supports.

2. In a machine of the class described, the combination of a frame, a shaft rotatably mounted thereon, a tool support carried by said shaft, a work support, a second shaft journaled on said frame, means carried by said second shaft for causing the relative reciprocation of said supports, a motor connected to rotate said first-mentioned shaft, a power-controlling device arranged intermediate said motor and the source of power, and coacting means on said frame and said second-mentioned shaft adapted to actuate said power-controlling device, whereby power is supplied to said motor only during a portion of the relative movement of said supports.

3. In a machine of the class described, the combination of a frame, a shaft rotatably mounted thereon, a tool support carried by said shaft, a work support, a second shaft journaled on said frame, means carried by said second shaft for causing the relative reciprocation of said supports, a fluid-driven turbine connected to said first-mentioned shaft, a fluid-controlling device arranged intermediate said turbine and the source of fluid supply, and coacting means on said frame and said second-mentioned shaft adapted to actuate said device, whereby fluid is supplied to said turbine only during a certain portion of the relative movement of said supports.

4. In a machine of the class described, the combination of a frame, a shaft rotatably mounted thereon, a tool support carried by said shaft, a work support, a second shaft journaled on said frame, means carried by said second shaft for causing the relative reciprocation of said supports, an air-driven turbine connected to said first-mentioned shaft, an air valve mounted on said frame 5 and interposed between said turbine and the source of air supply, a lever pivoted on said frame, a cam carried by said second-mentioned shaft and coacting with said lever for actuating said valve, whereby air is 10 supplied to said turbine only during a certain portion of the relative movement of said supports.
5. In a machine of the class described, the combination of a frame, a shaft rotatably 20 mounted thereon, a tool support carried by said shaft, a work support, a second shaft journaled on said frame, means carried by said second shaft for causing the relative reciprocation of said supports, an air-driven 25 turbine connected to said first-mentioned shaft, an air valve mounted on said frame and interposed between said turbine and the source of air supply, a spring normally urging said valve to cut off the supply of air 30 to said turbine, a lever pivoted on said frame adjacent to said valve, a cam carried by said second-mentioned shaft and coacting with said lever so as to open said valve and permit the delivery of air to said 35 turbine only during a certain portion of the relative movement of said supports.
6. In a machine of the class described, the combination of a frame, a tool support and a work support mounted thereon, mechanism 40 for shifting said supports relative to each other so as to bring the work into position to be acted upon by the tool, a motor for rotating said tool support, a work holder mounted on said work support and adapted 45 to have the work automatically fed therefrom, a stop for limiting the feeding of said work, pairs of jaws urged to clamp said work at both sides of the point upon which the tool is caused to act, and means for re- 50 tracting said jaws to permit the discharge of the completed article and the feeding of the work.
7. In a machine of the class described, the combination of a frame, a tool support and 55 a work support mounted thereon, mechanism for shifting said supports relative to each other so as to bring the work into position to be acted upon by the tool, a motor for rotating said tool support, a work holder 60 mounted on said work support and adapted to have the work automatically fed therefrom, a stop for limiting the feeding of said work, pairs of jaws urged to clamp said work at both sides of the point upon which 65 the tool is caused to act, and means for re-

tracting said pairs of jaws in succession whereby the finished article is first released to permit it to be discharged from the work support, and then to release the work to allow it to be fed along said holder.

70

8. In a machine of the class described, the combination of a frame, a tool support and a work support mounted thereon, mechanism for shifting said supports relative to each other so as to bring the work into 75 position to be acted upon by the tool, a motor for rotating said tool support, pairs of jaws arranged adjacent to said stop with their opposed faces in alinement with said work holder and adapted to clamp the work 80 at both sides of the point acted upon by the tool, one jaw of each of said pairs being fixed and the other jaw of each of said pairs being shiftable, means normally urging said shiftable jaws into their retracted positions 85 for releasing the work, and means controlled by said support-shifting mechanism for shifting said shiftable jaws into their clamping positions.

85

9. In a machine of the class described, the combination of a frame, a shaft rotatably mounted thereon, a tool support carried by said shaft, a work support mounted on said frame, a second shaft journaled on said frame, means carried by said second shaft 95 and adapted to cause the relative reciprocation of said supports, a work holder mounted on said work support and adapted to have the work automatically fed therefrom, a stop for limiting the feeding of said work, 100 pairs of jaws arranged adjacent to said stop with their opposed faces in alinement with said work holder and adapted to clamp the work at both sides of the point acted upon by the tool, one jaw of each of said pairs being fixed, the other jaw of each of said pairs being pivotally mounted, arms connected to said pivotally mounted jaws, means normally acting upon said arms so as to retract said pivotally mounted jaws from 105 their clamping positions, levers mounted on said frame and having one end of each bearing upon said arms, and cams carried by said second-mentioned shaft and bearing upon the other ends of said levers, whereby 110 said levers are actuated to cause said arms to shift said pivoted jaws into their clamping 115 positions.

115

10. In a machine of the class described, the combination of a frame, a shaft rotatably mounted thereon, a tool support carried by said shaft, a work support mounted on said frame, a second shaft journaled on said frame, means carried by said second shaft and adapted to cause the relative 120 reciprocation of said supports, a work holder mounted on said work support and adapted to have the work automatically fed therefrom, a stop for limiting the feeding of said work, pairs of jaws arranged adjacent to 125

125

- 5 said stop with their opposed faces in alignment with said work holder and adapted to clamp the work at both sides of the point acted upon by the tool, one jaw of each of said pairs being fixed, the other jaw of each of said pairs being pivotally mounted, arms connected to said pivotally mounted jaws, means normally acting upon said arms so as to retract said pivotally mounted jaws from 10 their clamping positions, levers mounted on said frame and having one end of each bearing upon said arms, and cams carried by said second-mentioned shaft and bearing upon the other ends of said levers, whereby 15 said levers are actuated to cause said arms to shift said pivoted jaws into their clamping positions, said cams being constructed so as to permit said pivoted jaws to be retracted in succession, first to release the completed article to enable it to be discharged from said work support, and then to release the work for the purpose of allowing it to be advanced.
11. In a machine of the class described, 20 the combination of a frame, a tool support and a work support mounted thereon, mechanism for shifting said supports relative to each other so as to bring the work into position to be acted upon by the tool, a motor for rotating said tool support, a work holder mounted on said work support and adapted to have the work automatically fed therefrom, a stop for limiting the feeding of said work, pairs of jaws urged to clamp said work at both sides of the point upon 25 which the tool is caused to act, means for retracting said jaws to permit the discharge of the completed article and the feeding of the work, an air blast arranged adjacent to said jaws, a valve mounted on said frame 30 and controlling said air blast, a lever pivoted on said frame adjacent to said valve, and a cam operated by said support-shifting mechanism and coacting with said lever so as to cause the opening of said valve to permit a jet of air to be directed against the finished article simultaneously with the retraction of the respective pair of jaws.
12. In a machine of the class described, 35 the combination of a frame, a tool support and a work support mounted thereon, mechanism for shifting said supports relative to each other so as to bring the work into position to be acted upon by the tool, a motor for rotating said tool support, a work holder mounted on said work support and adapted to have the work automatically fed therefrom, a stop for limiting the feeding of said work, pairs of jaws urged to clamp said work at both sides of the point upon 40 which the tool is caused to act, means for retracting said jaws to permit the discharge of the completed article and the feeding of the work, an air blast arranged adjacent to said jaws, a pair of valves mounted on said casing adjacent to each other, one of said valves being interposed between said turbine and the source of air supply, the other valve being adapted to control the air to said air blast, a pair of 45 levers pivotally mounted on said frame and adapted to control the respective valves, and a cam carried by said second-mentioned shaft and arranged to shift said levers and thereby actuate said valves so that air is delivered to said turbine only during a predetermined part of the relative movement of said supports and a jet of air is projected from said air blast simultaneously with the retraction of said jaws.

15. In a machine of the class described, the combination of a frame, a shaft journaled thereon, a tool support carried by said shaft, a motor connected to rotate said shaft, 5 a work support reciprocatingly mounted on said frame and comprising relatively adjustable parts, a shaft journaled on said frame, coacting means on said work support and said second-mentioned shaft for causing the 10 reciprocation of said work support, a rotating member on said work support adapted to be actuated for causing the relative shifting of said parts, and mechanism carried by said support and actuated by the reciprocation of 15 said work support for rotating said member.
16. In a machine of the class described, the combination of a frame, a shaft journaled thereon, a tool support carried by said shaft, a motor connected to rotate said shaft, 20 a work support reciprocatingly mounted on said frame and comprising relatively adjustable parts, a shaft journaled on said frame, coacting means on said work support and said second-mentioned shaft for causing the 25 reciprocation of said work support, a rotating member on said work support adapted to be actuated for causing the relative shifting of said parts, a ratchet carried by said rotating member, an oscillating member 30 mounted on said work support, a pawl carried by said oscillating member and arranged to engage said ratchet, and means on said frame engaging said oscillating member and adapted to oscillate the same through 35 the reciprocation of said work support on said frame.
17. In a machine of the class described, the combination of a frame, a shaft journaled thereon, a tool support carried by said shaft, a motor connected to rotate said shaft, 40 a work support reciprocatingly mounted on said frame and comprising relatively adjustable parts, a shaft journaled on said frame, coacting means on said work support and 45 said second-mentioned shaft for causing the reciprocation of said work support, a rotating member on said work support adapted to be actuated for causing the relative shifting of said parts, a ratchet carried by said 50 rotating member, an oscillating member mounted on said work support, a pawl carried by said oscillating member and arranged to engage said ratchet, a cam mounted on said frame, and a roller carried by 55 said oscillating member and engaging said cam, whereby said oscillating member is oscillated through the reciprocation of said work support on said frame.
18. In a machine of the class described, 60 the combination of a frame, a shaft journaled thereon, a tool support carried by said shaft, a motor connected to rotate said shaft, a work support reciprocatingly mounted on said frame and comprising relatively adjustable parts, a shaft journaled on said frame, 65 coacting means on said work support and said second-mentioned shaft for causing the reciprocation of said work support, a rotating member on said work support adapted to be actuated for causing the relative shifting of said parts, a ratchet carried by said rotating member, an oscillating member mounted on said work support, a pawl carried by said oscillating member and arranged to engage said ratchet, a cam mounted on said frame, and a roller carried by 70
- coacting means on said work support and said second-mentioned shaft for causing the reciprocation of said work support, a rotating member on said work support adapted to be actuated for causing the relative shifting of said parts, a ratchet carried by said rotatable member, an oscillating member mounted on said work support, a plurality of pawls on said oscillating member and adapted to engage said ratchet, said pawls being 75 of varying lengths so that the angular movement of said ratchet may be less than the length of a single tooth, and coacting means on said oscillating member and said frame, whereby said member is oscillated through 80 the reciprocation of said work support on said frame.
19. In a machine of the class described, the combination of a frame, a shaft journaled thereon, a tool support carried by said shaft, 85 a motor connected to rotate said shaft, a work support reciprocatingly mounted on said frame and comprising relatively adjustable parts, a shaft journaled on said frame, coacting means on said work support and said second-mentioned shaft for causing the reciprocation of said work support, a rotating member on said work support adapted to be actuated for causing the relative shifting of said parts, a ratchet carried by 90 said rotating member, an oscillating member mounted on said work support, a pawl carried by said oscillating member and arranged to engage said ratchet, a cam mounted on said frame, a roller carried by 95 said oscillating member and engaging said cam, whereby said oscillating member is oscillated through the reciprocation of said work support on said frame, means normally adapted to retract said pawl, a finger 100 normally urged to hold said means in its inoperative position, and coacting shoulders on said finger and said work support adapted to cause the retraction of said finger at a predetermined point in the relative shifting of said oscillating member and said work support.
20. In a machine of the class described, the combination of a frame, a shaft journaled thereon, a tool support carried by said shaft, a motor connected to rotate said shaft, 105 a work support reciprocatingly mounted on said frame and comprising relatively adjustable parts, a shaft journaled on said frame, coacting means on said work support and said second-mentioned shaft for causing the reciprocation of said work support, a rotating member on said work support adapted to be actuated for causing the relative shifting of said parts, a ratchet carried by 110 said rotating member, an oscillating member mounted on said frame, and a roller carried by 115 said oscillating member and engaging said cam, whereby said oscillating member is oscillated through the reciprocation of said work support on said frame.

said oscillating member and engaging said cam, whereby said oscillating member is oscillated through the reciprocation of said work support on said frame, a rod shiftably mounted on said oscillating member, a spring normally urging said rod to retract said pawl, a finger adapted to hold said rod in its inoperative position, and coacting shoulders on said finger and said work support adapted to cause the retraction of said finger at a predetermined point in the relative shifting of said oscillating member and said work support.

21. In a machine of the class described, the combination of a frame, a bearing supported on said frame, a vertically disposed shaft journaled in said bearing, a work support carried by said shaft, a disk-shaped tool mounted in said work support, a motor connected to rotate said shaft, a work support reciprocatingly mounted on said frame, a work holder mounted on said support and adapted to have work fed therefrom, clamping means for securing said work in position to be acted upon, mechanism for retracting said clamping means to permit the discharge of a finished article and the feeding of the work, a shaft journaled on said frame, co-acting means on said second-mentioned shaft and on said work support respectively adapted to cause the reciprocation of said work support so as to move the work toward the tool for the purpose of having sections severed therefrom, and means for retracting said clamping means so as to release the severed section.

22. In a machine of the class described, the combination of a frame, a tool support and a work support mounted thereon, mechanism for shifting said supports relative to each other so as to bring the work into position to be acted upon by the tool, a motor for rotating said tool support, a work holder mounted on said work support and adapted to have the work automatically fed therefrom, a stop for limiting the feeding of said work, pairs of jaws urged to clamp said work at both sides of the point upon which the tool is caused to act, means for retracting said jaws to permit the dis-

charge of the completed article and the feeding of the work, and other means adapted to be actuated so as to discharge the completed article from said jaws and stop.

23. In a machine of the class described, the combination of a frame, a tool support and a work support mounted thereon, mechanism for shifting said supports relative to each other so as to bring the work into position to be acted upon by the tool, a motor for rotating said tool support, a work holder mounted on said work support and adapted to have the work automatically fed therefrom, a stop for limiting the feeding of said work, pairs of jaws urged to clamp said work at both sides of the point upon which the tool is caused to act, means for retracting said jaws to permit the discharge of the completed article and the feeding of the work, and other means automatically actuated with the retraction of said jaws for discharging the completed article from said jaws and stop.

24. In a machine of the class described, the combination of a frame, a tool support and work support mounted thereon, mechanism for shifting said supports relative to each other so as to bring the work into position to be acted upon by the tool, a motor for rotating said tool support, a work holder mounted on said work support and adapted to have the work automatically fed therefrom, a stop for limiting the feeding of said work, pairs of jaws urged to clamp said work at both sides of the point upon which the tool is caused to act, means for retracting said pairs of jaws in succession whereby the finished article is first released to permit it to be discharged from the work support, and then to release the work to allow it to be fed along said holder, and a member carried by one of the jaws of said pair which is first retracted, said member being adapted to discharge the completed article from said pair of jaws and said stop.

Signed at Chicago this 17th day of June, 1919.

OSCAR ONSRUD.
